UNITED STATES PATENT OFFICE.

FREDERICK E. SEDDON, OF HOBOKEN, NEW JERSEY, ASSIGNOR TO GARVIN MACHINE COMPANY, A CORPORATION OF NEW YORK.

UNIVERSAL ANGLE-PLATE.

1,026,932.

Specification of Letters Patent.

Patented May 21, 1912.

Application filed August 11, 1911. Serial No. 643,496.

To all whom it may concern:

Be it known that I, FREDERICK E. SEDDON, a citizen of the United States, and resident of Hoboken, in the county of Hudson and 5 State of New Jersey, have invented certain new and useful Improvements in Universal Angle-Plates, of which the following is a specification.

This invention relates to an improved jig 10 or fixture for milling machines, grinding machines and the like, employed for reborning automobile cylinders, pump and steam engine cylinders, sleeves, collars and couplings of various sorts. 15 A large class of articles in mechanics, particularly automobile cylinders, are made with a bored portion, and a flange faced perpendicular to the bore and having bolt holes by which it is secured to another machine part. 20 This general plan of structure is a common one on account of the ease with which it is bored and faced in one operation in a lathe, and with absolute precision. On account of this ease and precision of manipulation, 25 bored parts having a perpendicular faced flange at one end with bolt holes, are common in all sorts of machinery. Now if it becomes necessary, by reason of wear, to re bore any such automobile cylinder or machine part, it 30 is evident that the flange is available as a guiding plane from which the bore may be carried in a perpendicular direction. The difficulty however is to get an adequate and adjustable holding means which will fix the 35 plane of this flange in a sufficiently accurate and positive manner in an ordinary milling or grinding machine, and be adapted for different kinds and sizes of mechanical bored and flanged parts on which repair may be 40 required.

It is the purpose of my invention to provide a jig or fixture for milling and grinding machines which will take work of any shape and size, within of course a reasonable 45 limit of magnitude, and hold such work with absolute precision; in other words, with the plane of the flanged portion perpendicular to the axis of the milling tool, and with as great firmness and rigidity as is requisite to 50 prevent any yielding.

It is further an object of the invention to provide a device of great simplicity and cheapness and durability, and which may be used with convenience and rapidity on 55 any standard milling or grinding machine.

With these objects in view, the invention consists in the improved jig or fixture as hereinafter more particularly set forth.

In the drawings,—Figure 1, is a plan view of a knee or universal angle plate embodying the principles of the invention; Fig. 2, 60 is a front elevation; Fig. 3, is a similar view showing its use with a different piece of work.

The best constructions embodying the invention will include a knee, preferably integral or in one piece, and having a flat base adapted to fit on the table of the milling machine. From the flat base there will project upward two uprights to a vertical distance about as great as the length of the base, with a considerable separation or clear space between them as hereinafter described. These uprights are braced by integral webs connected to the base in such a manner as 65 to be exceedingly rigid, particularly in use. In accordance with this construction the rigidity of the uprights may be made substantially as great at all points, as at points directly adjacent to the base. It will be appreciated that this rigidity is secured by the construction hereinafter described throughout as great a height as that just mentioned, and it will be further appreciated that no 70 greater height than this in the uprights will 75 be necessary on account of the principles of operation hereinafter stated. The drawings illustrate a knee having a base 1 and uprights 2, with integral webs 3 extending from the rear of the uprights toward the base. 80 In the best construction the webs will flare 85 outward from one another behind the uprights and proceeding toward the base. The result of this construction is that the web of one upright acts as a positive brace for the 90 web of the other upright when the knee is in use. In other words, each web and upright braces the other in the only direction where there is any possible weakness. The base 1 has openings 4 and 5 in the interest of lightness, and it is evident that the webs 3 may be correspondingly provided with openings 95 if desired.

6 denotes holes in the base through which T bolts may be passed to secure the base to 100 the milling machine table.

Each of the uprights 2 is accurately faced at 7 in a plane perpendicular to the bottom face of the base 1, and each upright further has means, such as a vertical T slot 8, cut 110

centrally on its finished or front face 7 so as to receive a clamping device at various positions vertically on the upright. There will also be provided four or more brackets 5 which have a slot or adjustment 10 extending longitudinally thereof, and a flat finished face 11 on one side. These brackets will further have holes 12 near one extremity, these holes being also perpendicular to the flat face 11 of the bracket. 10

13 denotes T bolts adapted to be received in the T slots 8 of the uprights 2 and passing through the slots 10 of the brackets 9. When these bolts are tightened the various 15 faces 11 of the brackets will be rigidly held in exactly the same plane, and this plane will furthermore be the plane of the finished faces 7 of the uprights. The holes 12 of the brackets will be located anywhere within 20 the open space between the uprights, their position depending merely on where the brackets happen to be clamped.

Assuming now that it is desired to reboore 25 a part of a machine, such as an automobile engine cylinder, the cylinder is merely roughly blocked in place within the knee so that the cylinder base flange is roughly in the plane of the faces 7. The various brackets will now be fastened to the usual 30 holes of the cylinder base flange by any convenient bolts. Thereupon the T bolts 13, which have been previously positioned in the brackets and in the T slots 8, will be firmly tightened, and by this act the finished faces of the various brackets and also 35 the bottom face of the cylinder base flange will be brought with great accuracy into the plane of the upright faces 7. This accuracy is secured notwithstanding the considerable 40 weight in the automobile cylinder, and the rigidity is so great that any suitable steady- 45 ing devices, such as screws 14, may be there- upon tightened without disturbing the accuracy of the first adjustment. In like manner the cylinder may be blocked up from below by any suitable wedge or screw. The larger the cylinder the shorter will be the projection of the brackets 9 beyond the uprights 2 and the greater the rigidity of their 50 action, so that with cylinders of consider- able size and weight, where the distorting strains are proportionately large, the rigidity will be proportionately intensified and rendered greater than the require- 55 ment for any occasion which may arise. It is further apparent that with cylinders cast *en bloc*, with three or four or six cylinders in a unit casting, the same knee may be used and the brackets 9 merely employed 60 with those holes of the cylinder base flange which are within their range of adjustment. This may allow a number of the cylinders to extend entirely above the knee, but these cyl-

inders will be sufficiently supported by the rigidity of the casting itself in view of the 65 fact that the lower part of the casting is so adequately supported and adjusted.

Claims:

1. A knee for holding flanged engine cylinders with their bores parallel to a given 70 axis, comprising a base, uprights integrally projecting therefrom, integral webs for bracing the uprights from the base, finished vertical plane surfaces on said uprights, brackets having flat inner faces, and means 75 for clamping the flat faces of said brackets in contact with the finished faces of said uprights, said brackets having perforations at their extremities, as and for the purposes set forth. 80

2. A knee for holding flanged engine cylinders with their bores parallel to a given axis, comprising a frame formed with an opening, T slots extending among a plurality of sides of said opening, brackets having longitudinal slots and holes, bolts in 85 said T and bracket slots, said brackets and frame being adapted to be clamped into engagement in various positions of adjustment by means of said bolts, and additional bolts 90 passed through the holes of said brackets to clamp the work thereto. 85

3. A knee for holding faced castings perpendicular to a given axis comprising a base, uprights, webs extending rearwardly 95 from the uprights toward the base and flaring outwardly from one another as they extend toward the base, and brackets, said brackets and uprights having finished plane surfaces and adapted to be clamped into engagement in various positions of adjustment in a plane perpendicular to the base, said brackets being clamped in engagement in every possible position within the plane of 100 said faces and within a certain radius of movement. 105

4. A knee for holding flanged engine cylinders with their bores parallel to a given axis, comprising a broad flat bottomed base having rigid vertical frame bars with finished faces perpendicular to a given axis, and T slots extending along a middle line 110 of said faces, brackets having longitudinal slots and holes at their extremities and having finished faces, and T bolts, said brackets 115 and frame bars being adapted to be clamped into engagement by said bolts in various positions of adjustment with their finished faces in contact. 115

Signed at New York, in the county of 120 New York, and State of New York this 8th day of August, A. D. 1911.
